CLAIM

The ornamental design for a disposable foil pan, as shown and described.

DESCRIPTION

FIG. 1 is a top perspective view of a bottom portion of a disposable foil pan in accordance with the invention shown; FIG. 2 is a top view of the bottom portion of a disposable foil pan of FIG. 1;

FIG. 3 is a bottom perspective view of the bottom portion of a disposable foil pan of FIG. 1;

FIG. 4 is a bottom view of the bottom portion of a disposable foil pan of FIG. 1;

FIG. 5 is a cross-sectional view of the bottom portion of a disposable foil pan taken through line 5-5 of FIG. 2;

FIG. 6 is a cross-sectional view showing an enlarged segment of the bottom portion of a disposable foil pan of FIG. 5;

FIG. 7 is a top perspective view showing an enlarged section of the bottom portion of a disposable foil pan of FIG. 1; FIG. 8 is a top perspective view of a bottom portion of a disposable foil pan in accordance with a second embodiment of the present invention;

FIG. 9 is a top view of the bottom portion of a disposable foil pan of FIG. 8;

FIG. 10 is a bottom perspective view of the bottom portion of a disposable foil pan of FIG. 8; and,

FIG. 11 is a bottom view of the bottom portion of a disposable foil pan of FIG. 8.

The broken lines are for the purpose of illustrating portions of the disposable foil pan and forms no part of the claimed design.
